UNITED STATES PATENT OFFICE.

VERNON ROYLE, OF PATERSON, NEW JERSEY.

SHUTTLE.

1,109,250.

Specification of Letters Patent. Patented Sept. 1, 1914.

Application filed October 19, 1912. Serial No. 726,791.

To all whom it may concern:

Be it known that I, VERNON ROYLE, a citizen of the United States, and resident of Paterson, in the county of Passaic and State of New Jersey, have invented a new and useful Improvement in Shuttles, of which the following is a specification.

My invention relates to shuttles and more particularly to a shuttle for use in a circular loom, the object being to provide for promptly separating the warp threads in advance of the thread guide and lay, to such an extent as will permit the weft thread to be pressed into close proximity to the weaving pin or core, and to provide at the same time for leading the thread into the thread guide and lay in a direction approximately tangent to the periphery of the weaving pin or core, without passing the thread through an eye in the thread-guide and lay.

A practical embodiment of the invention is represented in the accompanying drawings, in which,

Figure 1 is a top plan view of a pair of thread guide and lay holders with thread guides and lays attached thereto in the position which they assume when in operation, the bodies of their respective shuttles not being shown. Fig. 2 is a section in the plane of the line A—A of Fig. 1. Fig. 3 is a transverse section in the plane of the line B—B of Fig. 1. Figs. 4 to 10 inclusive are enlarged diagrammatical sections showing the position of the thread guide and lay with respect to the weft and warp threads and weaving pin or core; Fig. 4 being taken in the plane of the warp thread line *a*; Fig. 5 in the plane of the warp thread line *b*; Fig. 6 in the plane of the warp thread line *c*; Fig. 7 in the plane of the warp thread line *d*; Fig. 8 in the plane of the warp thread line *e*; Fig. 9 in the plane of the warp thread line *f*; and Fig. 10 in the plane of the warp thread line *g*.

As the two weft thread guides and lays and their respective holders are similar in structure, a description of one will be sufficient for both. The weft thread guide and lay is denoted as a whole by 1. In its face, toward the weaving pin or core 3, which face conforms throughout a portion of its length to the periphery of the weaving pin or core, there is formed a spiral groove 2, for receiving and laying the weft thread 4. At the end of the thread guide and lay,

where the thread 4 enters the groove 2, the groove is directed outwardly away from the weaving pin or core in a direction approximating a line tangent to the periphery of the weaving pin or core, as shown at 5. The thread guide and lay 1, is attached to its holder 6 by means of bolts 7 extending through from the back of the holder 6, and tapped into the back of the thread guide and lay 1, as clearly shown in Fig. 1. The holder 6 is provided with diverging arms 8 and 9, by means of which it is made fast to legs 10 and 11 on the body of the shuttle. The arm 8, to wit: the advance arm of the holder 6, is provided with a plurality of fences or warp spreaders denoted by 12 and 13, and a fence or spreader 14 is also carried by the holder 6, in proximity to the thread guide and lay 1, the said fence 14 being arranged to coact with the fences 12 and 13. These warp spreaders or fences 12 and 13 are arranged in planes approximately parallel to a plane tangent to the weaving pin or core 3, and the fence or spreader 14, from its advance end back to a point about midway of its length, is approximately parallel to the fences 12 and 13. The fences or spreaders 12, 13, 14, have their advance ends arranged in substantial alinement, the line of their advance ends being oblique to a radial line drawn from the center of the weaving pin or core, with the advance end of the upper fence 12 on a radial line in advance of the advance ends of the fences or spreaders 13, 14.

The preferred shape of the fences or spreaders 12, 13, 14, is clearly shown in Fig. 2, the advance end of the spreader 12 being fairly sharp to gradually separate the warp threads, while the advance end of the fence or spreader 13 is more blunt to continue the spreading operation, and the advance end of 14 which engages the warp threads in proximity to the point where the thread guide and lay is to press the weft thread into close contact with the weaving pin or core, has a blunt end for spreading the warp threads immediately in advance of the action of the thread guide and lay, and is so shaped as to maintain this spread while the thread guide and lay is placing the weft thread in position and forcing it by a screw or cam motion firmly against the preceding weft thread. Furthermore, the positions of these several fences approximately parallel to a plane tangent to the periphery of the weav-

ing pin or core and hence oblique to the radial lines which the warp threads assume, serve to spread the warp threads to the desired extent during the movement of the 5 shuttle through a short arc, so that there may be ample time for the return of the warp threads and a re-crossing of the same while in advance of the on-coming shuttle. This provides against any possible failure 10 in effecting a perfect separation of the warp threads and it also provides for a gradual but rapid spreading of the threads to their maximum opening in proximity to the thread guide and lay, so that the latter may 15 do its work effectively. The weft thread 4, after passing over a guide pulley 15, leads inwardly along a groove 16 in the thread guide and lay holder and thence uninterruptedly into the open end 5 of the groove 20 2 in the face of the thread guide and lay. The weft thread is then free to render from the guide pulley 15, to the thread guide and lay, the absence of the eye heretofore common, freeing the thread from any liability 25 of obstruction due to any small nick or unevenness in the thread, the direction of the thread from the guide pulley 15 to the point where it is finally pressed into position in the woven fabric departing but little from a 30 straight line.

The views 4 to 10 inclusive, show the gradual action of the thread guide and lay and its holder on the weft thread from the time the fence or spreader 14 enters between the 35 warp threads up to the time when the weft thread is forced into its position relative to weft threads which have been previously laid. In these views the upper and lower warp threads are denoted respectively by 17 40 and 18.

What I claim is:

1. A shuttle provided with a thread guide and lay, the said thread guide and lay having an open groove in its forward end.
2. A shuttle provided with a thread guide and lay having an open groove in its forward end, the said forward end of the thread guide and lay having its face directed away from the core in a plane approaching a tangent to the periphery of the weaving pin or

core about which the thread guide and lay is intended to operate.

3. A shuttle provided with a thread guide and lay and a holder for the said thread guide and lay, the said holder having its 55 advance edge oblique to a radial line drawn from the center of the weaving pin or core about which the thread guide and lay is intended to operate, the outer portion of the said holder being on a radial line in advance 60 of the inner portion of the said holder.

4. A shuttle provided with a thread guide and lay and a holder for the same, the said holder being provided with a plurality of warp spreaders or fences. 65

5. A shuttle provided with a thread guide and lay and a holder for the same, the said holder being provided with a plurality of warp spreaders or fences located in planes substantially parallel to a plane tangential 70 to the periphery of the weaving pin or core about which the thread guide and lay is intended to operate.

6. A shuttle provided with a thread guide and lay and a holder for the same, the said 75 holder being provided with a plurality of tapered warp spreaders or fences gradually increasing in bluntness from the outer fence to the inner fence.

7. A shuttle provided with a thread guide 80 and lay and a holder for the same, the said holder being provided with a plurality of warp spreaders or fences arranged to act successively on the warp threads.

8. A shuttle provided with a thread guide 85 and lay and a holder for the same, and means for directing a weft thread to the advance end and thence to the face of the said thread guide and holder, the advance end of said thread guide and holder being 90 located in position to guide the weft thread through the warp shed.

In testimony, that I claim the foregoing as my invention, I have signed my name in presence of two witnesses, this sixteenth day 95 of October 1912.

VERNON ROYLE.
